UNITED STATES PATENT OFFICE.

BENJAMIN F. MAYO, OF SALEM, MASSACHUSETTS, ASSIGNOR TO THE MCKAY SHOE MACHINERY COMPANY, OF PORTLAND, MAINE, AND BOSTON, MASSACHUSETTS.

DESIGN FOR A PROTECTIVE SLUG.

SPECIFICATION forming part of Design No. 30,843, dated May 23, 1899.

Application filed April 28, 1899. Serial No. 714,699. Term of patent 14 years.

To all whom it may concern:

Be it known that I, BENJAMIN F. MAYO, a citizen of the United States, residing at Salem, in the county of Essex and Commonwealth of Massachusetts, have invented and produced a new and original Design for a Protective Slug, of which the following is a specification.

Figure 1 shows in end view a protective slug, illustrating my design; and Fig. 2 shows the same in elevation viewing it in the direction of its open wings.

The leading feature of my design for a protective slug consists of an elongated body bent at two points to present a circular head, said circular head having connected with and extended from each end thereof a concavo-convex wing.

The protective slug comprises an elongated body bent at *a b* to form a substantially-circular head *c*, the ends of said body, commencing at said bends, being provided with concavo-convex wings *e f*.

Having fully described my design, what I claim, and desire to secure by Letters Patent, is—

The design for a protective slug, substantially as herein shown and described.

In testimony whereof I have signed my name to this specification in the presence of two subscribing witnesses.

BENJAMIN F. MAYO.
